Howard A. Rose,

Inventor

UNITED STATES PATENT OFFICE.

HOWARD A. ROSE, OF FORT SCOTT, KANSAS.

DOOR-SECURER.

1,065,396.

Specification of Letters Patent. Patented June 24, 1913.

Application filed August 1, 1912. Serial No. 712,826.

To all whom it may concern:

Be it known that I, HOWARD A. ROSE, a citizen of the United States, residing at Fort Scott, in the county of Bourbon and 5 State of Kansas, have invented a new and useful Door-Securer, of which the following is a specification.

This invention relates to improvements in contrivances or devices known as door-se- 10 curers.

The invention has for its object to provide for effectively securing, without the use of a key, a door against clandestine or unauthorized opening.

15 A further object is to simplify the construction and arrangement of the parts, and to minimize the cost of manufacture.

A still further object is to provide for readily applying the device for use, also to 20 effect its removal with facility from within.

Other objects of the invention will be apparent as the nature thereof is more fully disclosed by the following description.

The invention consists of certain instru- 25 mentalities and features substantially as hereinafter fully described and defined by the appended claims.

In the accompanying drawing, illustrating 30 the preferred embodiment of my invention wherein it will be understood that various changes and modifications may be made as to the detailed construction and arrangement of the parts without departing from the spirit thereof, Figure 1 is a plan view of 35 the invention; Fig. 2 is a side elevation of the same, with the parts in position for insertion between the door and jamb; Figs. 3 and 4 are perspective views thereof, with the toothed or ratchet members separated.

40 In carrying out my invention, I suitably stamp or cast from sheet-steel, or other suitable metal, three pieces or members, two of which may be in the form of, and each termed as a bar, designated by 1 and 2, re- 45 spectively, while the third is a sleeve or collar 3 receiving, and slidable upon the first two members.

The two members 1 and 2 have outstanding therefrom, at right angles to their 50 lengths, plate-like projecting tongues or studs 4 and 5, respectively, said tongues or studs extending from opposite sides of said members, however.

55 The striking or "blanking" up of the tongue or stud 4 leaves an orifice 6 in the member 1, of course, of corresponding out-

line, said tongue being preferably quad- 60 rangular in outline and, in performing its function, is received by the bolt-receiving mortise or keeper of the "striking" plate, which will again be referred to later.

The tongue 5 of the member 2 terminates one end thereof and, when in its effective position, is adjusted against or in contact with the door, as will be further noted 65 presently.

The tongue or projection 5 extends be- 70 yond its carrying member 2 and abuts or is presented edgewise or at a right angle to the member 1, thus giving it a greater locking or door-engaging area than would other- 75 wise be the case.

The members 1 and 2 are disposed edge- 80 wise with respect to each other, and the opposed edges thereof are furnished with serrations, teeth or ratchet surfaces, prefer- 85 ably saw-tooth like and designated as 7 and 8, respectively, said serrations or ratchet- surfaces being adapted to intermesh or interlock. The serrations or teeth 7 of the member 1 extend practically throughout the length thereof, while the teeth 8 extend only a fraction of the length of the member 2 as shown, the same serving, in connection with the sleeve or collar 3, before referred to, for 90 effecting the locking action upon the door, or the holding of the two members 1 and 2 interlocked at the extreme outer end of the member 1 to provide for the retention of the inner end or tongue 5 of the member 2 suf- 95 ficiently removed from the inner end or tongue 4 of the member 1 to allow of the convenient or ready insertion or adjustment of the tongue 4 of the member 1 into the bolt mortise or keeper.

The member 2, which is provided at its extreme outer end, with a finger-loop 9, or which may serve for its suitable suspension in place when not in use, has a cross-stud or pin 10 adjacent said finger-loop or end, 100 to prevent the casual displacement of the slidable sleeve-member 3, as will be readily appreciated.

In applying the device for use, it is only required, by placing the door in partially 105 open position, and after adjusting the parts in the last referred to position, to insert the tongue 4 into the bolt mortise or keeper, then close the door against the member 1, which will wedge or jam said tongue in 110 place; the sleeve-member 3 is now to be slid to the extreme outer end of the member 2

releasing said member, it being retained from dropping to the floor by the hand; said sleeve-member is held to its outermost position upon the member 2, and the member 5 2 then adjusted in position, with its tongue 5 against the door, the sleeve member finally being moved into its innermost position, which will effect the interlocking of the members 1 and 2, and accordingly the 10 tongue 5 against the door and it, in turn, locking the tongue 4 in the bolt keeper or mortise.

In order to remove the device and accordingly unlock the door, it is only required to move the sleeve 3 to its outermost position, thus providing for the separation of the interlocked members 1 and 2, which will allow of the outward movement of the member 2 and the disengagement of the 20 tongue 5 from the door, when the door may be opened and the member 1 readily removed, together with the other members of the device.

What is claimed is:—

25 1. A door securer, including two interlocking members, each of which has an outstanding tongue at right angles to the body portion of the member, said members being positioned in such relation that the 30 two tongues are disposed in opposite directions, and a sleeve surrounding the adjacent portions of the members to hold the members together.

35 2. A device of the type described, including two interlocking bar-members having oppositely extending tongues, respectively, near one, and the corresponding end, and a sleeve slideable upon the bar-members and aiding to produce their interlocking action, 40 said bar-members having intermeshing teeth to effect such interlocking action.

3. A device of the type described, includ-

ing two interlocking bar-members, with intermeshing teeth therebetween, the teeth of one bar-member extending only through 45 part of its length, and the teeth of the other bar member extending through its entire length, said bar-members having oppositely extending right angled tongues, respectively, arranged with respect to one, and the corresponding end, and a sleeve slideable upon said bar-members for aiding the locking action therebetween.

4. A device of the type described, including two bar-members intermeshed for interlocking action and having oppositely extending right-angled tongues arranged with respect to one, and the corresponding end thereof, a sleeve slideable upon, and aiding to produce the interlocking action between said bar-members, one of said bar-members having a finger-looped end and a cross-stud at said end adapted to form a stop for said sleeve to guard against its casual displacement.

5. A door securer, including two plates, coacting means carried thereby to permit the interlocking of the plates; a tongue formed at right angles to the body of each plate, said tongues when the plates are interlocking extending laterally of the plates and in opposite directions, the tongue of one member being of greater width than its carrying plate, to, when the plates are interlocked, be positioned, at right angles to the other plate, and a sleeve slideable upon said plate to aid in the interlocking action.

In testimony that I claim the foregoing as my own, I have hereto affixed my signature in the presence of two witnesses.

HOWARD A. ROSE.
